United States Patent Office

Des. 182,839
Patented May 20, 1958

182,839

COMMODE

John J. Lubberts and Lambert J. Mulder, Grand Rapids, Mich., assignors to Tomlinson of High Point, High Point, N. C., a corporation of North Carolina

Application March 20, 1957, Serial No. 45,351

Term of patent 14 years

(Cl. D33—19)

FIG. 1.

Figure 1 is a front perspective view of the commode embodying our new design showing the sliding panels on the top and front of the commode; and

We claim:

The ornamental design for a commode, substantially as shown.
